OPHTHALMIC MOUNTING

Robert James Fleming, London, England, assignor to American Optical Company, Southbridge, Mass., a voluntary association of Massachusetts

Application September 1, 1932, Serial No. 631,346

2 Claims. (Cl. 88—43)

This invention relates to improvements in ophthalmic mountings and has particular reference to new and improved guard arm and bridge connections for the same.

5 This application is a continuation of my application Serial Number 295,750, filed July 27, 1928.

The principal object of the invention is to provide new and improved guard arm and bridge 10 connections which may be made of bar material as distinguished from stamped or cut out material so that, in the case of the use of material having a base metal core and a precious metal exterior, there will be no exposed base metal at 15 the edges of the parts.

Another object of the invention is to provide improved means for connecting the bridge of an ophthalmic mounting to accommodate the brow or forehead configuration of the wearer.

20 Another object of the invention is to provide improved means for connecting the bridge and for adjusting the lenses of an ophthalmic mounting.

Another object of the invention is to provide 25 simple, efficient and economical means of connecting the guards and bridges of ophthalmic mountings to fit various facial requirements and to make desired adjustments therefor.

Another object of the invention is to provide 30 improved means whereby bridges of various sizes may be attached to an ophthalmic mounting.

Another object of the invention is to provide improved means whereby various types of guards may be applied to an ophthalmic mounting.

35 Another object of the invention is to provide improved means for varying the distance between the lenses of an ophthalmic mounting.

Another object is to provide adjustable means 40 for varying the inset and outset of the bridge to accommodate the brow or forehead of the wearer.

Another object of the invention is to provide different types of lens connections such as rimless, composition rims, metallic rims and combined metallic and non-metallic rims.

Another object of the invention is to provide 45 simple, economical and efficient means for connecting the guard arms and bridge to an ophthalmic mounting and for forming the parts thereof whereby the cost of material and assembling operations are greatly reduced.

Another important object of the invention is to reduce the capital investment of the dealer in 50 the amount of stock necessary to meet various

dimensional requirements and variations in personal taste of design.

Other objects and advantages of the invention will be apparent from the following description taken in connection with the accompanying drawings, and it will be apparent that many changes may be made in the arrangements of parts and details of construction without departing from the spirit of the invention as expressed by the accompanying claims. I, therefore, do not wish to be limited to the exact details and arrangements shown and described as the preferred forms only have been shown by way of illustration.

Referring to the drawings:

Fig. I is a rear perspective view of an ophthalmic mounting embodying the invention;

Fig. II is an enlarged sectional elevation on line II—II of Fig. I;

Fig. III is an enlarged partial plan view of Fig. I, partly shown in section;

Fig. IV is a perspective view similar to Fig. I of a modified form of the invention;

Fig. V is an enlarged sectional elevation on the line V—V of Fig. IV;

Fig. VI is an enlarged partial plan view of Fig. IV shown partly in section;

Fig. VII is a rear elevation of an ophthalmic mounting showing another modified form of the invention;

Fig. VIII is an enlarged sectional elevation on the line VIII—VIII of Fig. VII;

Fig. IX is an enlarged sectional elevation on line IX—IX of Fig. VII;

Fig. X is an enlarged partial plan view of Fig. VII;

Fig. XI is a fragmentary perspective view of another modified form of the invention;

Fig. XII is a sectional view of the line XII—XII of Fig. XI;

Figs. XIII, XIV and XV are views similar to Fig. XII illustrating further modifications of the invention;

Fig. XVI is a front elevation of a separate bridge bar member;

Fig. XVII is a view similar to Fig. XVI showing another form of bridge bar member;

Fig. XVIII is a view similar to Fig. VIII showing how the position of the attachment of the bridge to the guard arm may be varied;

In the fitting of ophthalmic mountings it has been found from experience that it is very difficult if not practically impossible for a wearer to obtain a mounting exactly fitted to his facial requirements of the particular design which he

desires. The distance between the eyes varies in different people; the brow configuration is different in different people; the types of noses vary in different people; and the tastes of different people vary as to the configuration and design of the mounting. It is, therefore, desirable that provision be made by which the dispensing optician by simply carrying a number of different parts can assemble them to the facial requirements and the design desired. This reduces the investment in stock carried by the dispensing optician and gives the wearer a better fit and a mounting to his satisfaction as regards design of the same.

If the parts of such a mounting can be made of a material having a base metal core and a precious metal outer surface commonly known in the art as filled material the price can still further be reduced, the wearer obtaining all the advantages of the precious metal and its wearing qualities without having the exposed base metal parts coming in contact with the skin, which is liable to cause injurious effects due to the action of perspiration on the base metal.

It is, therefore, the prime object of my invention to provide new and improved guard arm and bridge connections for ophthalmic mountings overcoming all the disadvantages of the prior art and obtaining the advantages of facilitating assembly and the use of filled material, as set forth hereinabove. It will readily be seen that with such arrangements I can provide not only the necessary clearances, size and adjustments, but also any desired design of bridge or guard, making the adaptability of the mounting practically universal and reducing greatly the investment in stock of material which the dispensing optician has to carry.

The primary feature, therefore, of the present invention is the production of an ophthalmic mounting of the type above described which is characterized in that the bridge and guard arms are formed of separate pieces of material and in the finished article are as respects the guard arms soldered or otherwise secured to the lens rims or lens mountings, and as to the bridge connected, for example, soldered, screwed or riveted to the guard arms. This arrangement is simple and cheap to manufacture and can be made up in attractive forms as hereinabove referred to. For a more complete understanding of this and other features of the invention there will now be described by way of example only certain constructional forms of ophthalmic mountings according to the invention. It is to be understood, however, that the invention is not restricted to the precise construction and details set forth.

Referring to the drawings wherein similar reference characters denote corresponding parts throughout, it will be noted that the invention consists primarily in an arm carrying the nose guard, said arm being secured to the mounting and a separable bridge member attached to the guard arms.

The construction shown in Figs. I, II and III comprises a pair of lens rims 1 having the usual temples 2 secured thereto by the endpiece members 3. The lens rims 1 are connected centrally by the bridge member 4 having the cross arch portion 5 and the descending portions 6, the ends of the descending portions being widened or broadened out to form a rivet or screw connection 7. The guard arms 8 are bent into a box form 9 in which the widened or broadened out ends of the descending portions 6 are secured by

any suitable means, such as a screw or rivet 10. The end of the box form 9 is soldered or otherwise secured to the lens rim 1 at the point 11 and the guard 12 is secured to the opposite end of the guard arm 8. This connection may be solid or pivoted as desired. The mounting is assembled by placing the widened end of the descending portion 6 in the box 9 and securing it therein by the screw 10.

It will be seen that while the guard arms 8 are rigidly secured to the lens rims 1 in this construction, the ends of the bridge are separately attached to the guard arms and, therefore, different widths of bridges, different designs of bridges and bridges of different insets and outsets may be used to provide for the individual taste of the wearer and for this facial characteristic.

In Figs. IV, V and VI, I have shown the guard arms 8 secured to the inner rim of a combined metal and non-metallic lens rim. The said rim comprises the inner rim 13 of metal having a suitable lens groove in which the lens 14 is seated and an outer rim 15 of celluloid or other non-metallic material fitting thereover. The guard arm 8 is soldered or otherwise secured to the inner metal rim at 16 so that the non-metallic rim 15 may fit therearound. In this construction the ends of the bridge are soldered to the guard arms at 17. This provides a convenient and neat attachment for the so-called combination or inner rim constructions. The bridge 4 is separate from the guard arm and bridges of different designs, sizes and widths may, therefore, be used to provide for the individual taste of the wearer and to fit various facial requirements. The bridge may also be soldered at various points between the rim and the guard 12 to provide any desired inset or outset, making a facile and simple way of providing for the brow or forehead clearance.

In Figs. VII, VIII, IX and X, I have shown the guard arm 8 secured to a clamp 18 adapted to fit around and hold the cellulose or composition rims 19. The bridge is soldered or otherwise secured to the guard arm 8 as in the case of the device shown in Fig. V, and the guard 12 is likewise secured to the end of the guard arm.

In Figs. XI and XII, I have shown the guard arm 8 as secured at 21 to the inner metallic rim 13 of a combined metallic and non-metallic ophthalmic mounting. The guard arm 8 is provided with a slot 22 and teeth 23 over which the box end 24 of the bridge is fitted, it being held thereon by the screw 25. The box end 24 of the bridge is formed by widening and bending the end of the descending portion 6 and is provided with suitable teeth 26 which interlock with the teeth 23 on the guard arm. This provides a rigid connection between the bridge and guard arm and it is clear that the box end of the bridge may be adjusted in any desired position between the rim and guard. Provision is thereby made for adjustment of the bridge to the desired inset or outset to accommodate the brow or forehead configuration of the wearer and also allows the use of various sizes and styles of bridges.

In Fig. XIII, the guard arm 8 is provided with a forward loop 27 attached at 28 to the front of the lens rim 1. This provides means of varying the distance between the lenses to accommodate the pupillary distance of the wearer. The adjustment is made by bending the guard arm 8 to increase or decrease the size of the loop.

In Fig. XIV the guard arm 8 is provided with a rearward loop 29 to which the guard 12 is loosely attached so that it may automatically adjust itself to the nose of the wearer. The 5 loop 29 provides means of varying the position of the guard to accommodate variations in the shape of the nose and other facial variations.

In Fig. XV the guard arm 8 is provided with the forward loop 27 and rearward loop 29 to give 10 the combined adjustments of the devices shown in Figs. XIII and XIV. The position of the attachment of the bridge to the guard arm may also be varied as in the case of the device shown in Figs. VIII and IX. The guard 12 is rigidly secured 15 at 30 to the end of the guard arm 8 and the position of the guard with respect to the nose of the wearer is controlled by adjusting the loop 29.

Fig. XVI illustrates the bridge member shown 20 throughout the invention, and Fig. XVII illustrates a modified form of bridge member. These bridge members are made in various sizes and designs and are attached to the guard arm 8 as previously described.

25 In Fig. XVIII, I have shown the guard arm 8 secured to the ordinary lens clip or clamp 31 of a rimless mounting, the same being made integral therewith or soldered or otherwise secured to the lens clip. The bridge is soldered or connected to the guard arms as in the case of the 30 previously described constructions, and the guard 12 is attached at its top to the end of the arm 8.

From the foregoing description it will be seen 35 that I have provided simple, efficient and economical means for carrying out and obtaining all the advantages of the invention, particularly of providing means by which bridges, guards and arms of various sizes, shapes and designs may be used and so connected as to clear the brow and 40 facial configurations of the wearer and by which means the position of the guards, lenses and heights of bridges may be obtained.

It will be clear that my invention is applicable 45 to practically all forms and types of ophthalmic mountings wherein the lenses are connected by a bridge and secured in place on the face by guard and guard arm connections.

Having described my invention, I claim:

1. In a device of the character described, a 50 pair of separated lens holding members, a bridge member extending between the lens holding members and connecting the same and comprising a central bridge portion arched to fit around

the nose in the horizontal plane, the end portions thereof extending rearwardly of the lens holding means and thence downwardly to a bifurcation, one arm of the bifurcation extending forwardly and upwardly to the lens holding member, and the other arm of the bifurcation extending rearwardly and downwardly to a loop, thence forwardly to a guard connection and a nose guard secured to the said guard connection, 80 said downwardly extending parts of the bridge and said two arms of the bifurcation all lying in substantially the same vertical plane substantially normal and tangent to the nasal sides of the lens holding means to leave clear the nose space between them and said portion between the branch and the end of the bridge portion being adjustable by bending to position the bridge portion towards or away from the plane of the lens holding means and to increase or decrease the distance between the lens holding means, and also to position the guard towards or away from the plane of the lens holding means and said loop portion of the rearward arm of the bifurcation being adjustable by bending to 85 raise, lower, or incline the nose guard with respect to the nose.

2. In an ophthalmic mounting, means for holding a pair of lenses and bridging and nose guard means comprising a bridging portion extending between the lens holding means in substantially a horizontal direction and arched to the cross section shape of the nose, the ends of said portion extending to the rear of the plane of the lenses, then extending substantially vertically downward and substantially parallel to the plane 100 of the lenses and spaced rearward thereof and lying substantially in a plane normal to the edges of the lenses, said downward portion extending to a bifurcation, one portion of the bifurcation extending forwardly and upwardly to the lens holding means, and the other portion extending downwardly and rearwardly to a loop and thence 105 forwardly to a nose guard connection, and a nose guard secured to the nose guard connection, said downwardly extending portion of the bridge portion and upwardly extending bifurcation and lens holding means forming a substantially U shaped loop lying substantially in a plane normal to the edge of the lens, and said rearwardly extending bifurcation forming a loop member with its end 110 extending forwardly and lying substantially in a plane oblique to the plane of the lenses.

ROBERT JAMES FLEMING.
